TYPEWRITER CALCULATING MACHINE

Application filed March 9, 1927, Serial No. 174,018, and in Germany March 11, 1928.

This invention relates to typewriter calculating machines and has for its object to provide a mechanism for transmitting the numeral values set up by the depression of keys 5 to the counting mechanism, the main transmission members being a stepped roller and a setting wheel capable of sliding longitudinally of the said roller.

The known arrangements of this kind, in 10 which the sliding motion of the setting wheel for setting it in correspondence with the numeral value with respect to the stepped roller is derived from the motion of the key through cams, slotted guides, toothed gearing 15 and the like, besides being extremely complicated have the disadvantage that a considerable expenditure of force is required for depressing a key, thus also increasing the time required for carrying out the various calculating operations.

In contradistinction thereto the arrangement according to the present invention is very simple in construction, has a very light touch and enables the various calculations to 25 be carried out very rapidly.

These advantages of the new arrangement are obtained according to the present invention by the rotary motion of the stepped roller and the sliding motion of the setting wheel 30 being produced at the same time by the power drive which can be put in operation in a known manner, for instance on a key being depressed by raising the bars of a tabulator-like arrangement. The raised tabulator bar 35 forms a stop for checking the sliding motion of the setting wheel in correspondence with the numeral value set up by the depression of the key, this sliding motion taking place by utilizing the untoothed part of the stepped roller, so that the latter can have a rotating 40 action on the setting wheel only after the sliding motion is completed.

In the accompanying drawing a constructional form of the arrangement according to 45 the present invention is shown;

Fig. 1 being a plan view of the mechanism for transmitting the numerical values.

Fig. 2 a cross-section on line 2—2 of Fig. 1,
Fig. 3 a front elevation of a detail of Fig. 1.
50 Figure 4 is an end view of a detail.

In the cheeks 3 for journalling the shaft 1 of the stepped roller and the other transmission shafts of the calculating mechanism, which are fixed on the supporting plate 2, a bar 4 is arranged so as to be slidable longitudinally parallel to the axis of the stepped roller. A forked member 5 on the bar 4 engages on either side of the setting wheel 7 which meshes with the stepped roller 6, which wheel 7 is mounted on the driving shaft 8 so as to be capable of sliding, but not of 55 rotating thereon.

At the left-hand end of the bar 4 is a stop member 9 which, when the bar is released by the driving mechanism to be described below consequently is displaced to the right under the action of a tension spring 10. The movement of the bar 4 is checked by means of stop bars 11 which are operatively connected to the numeral keys by means of 60 intermediate connecting members, so as to be capable of being raised into the path of the stop member 9 by the depression of the numeral keys, the sliding motion of the bar and of the setting wheel being thus checked 65 in the position corresponding to the numeral values set up by the depression of the key.

In the normal position of the parts, a second stop member 12 on the bar 4 under the action of the spring 10 engages with the pin 80 13 on the rotary disc 14, the said pin and rotary disc being in the position shown in Figure 1. The rotary disc is mounted loosely on the hub 15 of a toothed wheel 16, the rim 17 of the rotary disc being connected to the hub 85 by a spiral spring 18.

By a toothed wheel 19 which meshes with the toothed wheel 16 and is of the same size as the latter and a bevel wheel gear 20 the toothed wheel 16 is in operative connection 90 with the driving shaft 1 of the stepped roller 6, the ratio of transmission being 1:1.

The driving shaft 1, which by means of a known driving mechanism performs one revolution at each depression of the key or for 95 each calculating operation, thus also causes the stepped roller 6 to perform one revolution.

The driving shaft 1 produces through toothed wheel gearing 24 a single revolution of a cam disc 25 of the shape shown in end 100

view in Fig. 4. Against this cam disc 25 there rests, when the mechanism is at rest and the disc is in the position shown in Fig. 4, the roller on the end of a lever 26 mounted a 5 on a shaft 21. On the shaft 21 is mounted a lever 22 which is at right angles to the lever 26 and which, when the roller on the lever 26 rests on the circular part of the periphery of the cam disc 25 when the latter is turned 10 in the direction of the arrow ω is rocked into the path of a boss 23 on the rotary disc 14 at 90° to the pin 13 and snaps back into the position shown in Fig. 4 under the action of a spring after the disc 25 has completed its 15 revolution.

The arrangement operates in the following manner:

On one of the stop bars 11 being raised by a depression of the corresponding numeral 20 key the power drive is put in operation through mechanisms of a known kind and the toothed wheel 16 is caused to perform one revolution.

At the commencement of the movement of 25 the stepped roller 6, one tooth of the setting wheel 7 is in engagement between the longest and shortest tooth of the stepped roller. As the rotary disc 14 is operatively connected to the shaft 1 of the stepped roller, the former 30 will also be rotated, the pin 13 allowing the bar 4 to move to the right, carrying the setting wheel 7 along with it. If not prevented by the extreme left hand stop bar 11 from doing so, the wheel 7 will be moved to the 35 right out of engagement in the gap between the shortest and longest teeth and will be slid along the stepped roller out of engagement with the teeth thereof.

During the first half revolution of the 40 toothed wheel 16, i. e. until the boss 23 strikes the lever 22, the rotary disc 14 will be carried round, the pin 13 releasing the stop member 12, so that the bar 4 is slid to the right under the action of the spring 10, until the 45 stop member 9 thereon strikes against the raised stop bar 11. This causes the setting wheel to be slid to that part of the stepped roller 6 which corresponds to the numeral value set up by the depression of the key. 50 If the setting wheel 7 is prevented by the extreme left hand stop member 11 from moving out of engagement with the teeth of the stepped roller, then all the teeth of the stepped roller will act on the setting wheel 55 and will turn it through an angle corresponding to nine teeth, the extreme left hand stop member 11 being operatively connected to the figure nine numeral key. If, on the other hand, a stop member belonging to a numeral 60 key having a lower value be moved into the path of the stop member 9, the bar 4 will move to the right under the control of the pin 13 on the disc 14. As the circumferential velocity of the pin 13 is at least twice that of 65 the teeth of the stepped roller, the sliding

motion of the setting wheel 7 takes place more rapidly than the engaging movement of the teeth, so that the setting wheel comes out of engagement with the teeth of the stepped roller. This sliding motion takes place exceedingly rapidly along the untoothed portion of the stepped roller, so that during the sliding motion the stepped roller cannot act on the setting wheel. After the completion of the sliding motion, the numeral value set up is transmitted by the stepped roller to the setting wheel and by the latter through the shaft 8 to the counting mechanism.

During the second half of the revolution 80 of the toothed wheel 16 the spiral spring 18 is stressed, while the rotary disc 14 is kept stationary by the lever arm 22 engaging with the boss 23.

Immediately before the completion of the 85 revolution of the toothed wheel 16, as already explained above, the roller on the lever 26 snaps back into the position shown in Figure 4 and the lever arm 22 releases the boss 90 23, whereby the rotary disc 14 under the action of the unwinding spiral spring 18 rapidly performs the second half of its revolution, i. e. snaps back into the initial position (Fig. 1).

At the same time the pin 13 strikes against 95 the stop member 12 and returns the bar 4 with its stop member 9 and the setting wheel 7 rapidly into the initial position, in opposition to the spring 10.

It should be understood, that the entire 100 operation described, which takes place on a numeral key being depressed, occupies no more than a fraction of a second.

What I claim is:

1. In a typewriter calculating machine, a 105 device for transmitting to a counting mechanism the numerical values set up by the numeral keys, comprising the combination with a stepped roller capable of being operatively connected to and disconnected from a power driving mechanism and a setting wheel operatively connected to the stepped roller for transmitting the motion of said roller to the counting mechanism, said setting wheel being capable of sliding longitudinally of said stepped roller, of means operatively connected to the said power driving mechanism for sliding the setting wheel simultaneously with the rotary movement of the stepped roller and means operatively connected to the numeral keys for arresting the sliding movement of the setting wheel, as and for the purposes set forth.

2. In a typewriter calculating machine, a 120 device for transmitting to a counting mechanism the numerical values set up by the numeral keys, comprising the combination with a stepped roller capable of being operatively connected to and disconnected from a power driving mechanism and a setting wheel oper- 130

- atively connected to the stepped roller for transmitting the motion of said roller to the counting mechanism, said setting wheel being capable of sliding longitudinally of said stepped roller, of means operatively connected to the said power driving mechanism for sliding the setting wheel simultaneously with the rotary movement of the stepped roller out of engagement with the teeth of said stepped roller, said sliding means comprising a bar 5 engaging the setting wheel, a stop member on said bar and tabulator bars operatively connected to the numeral keys and capable of being raised by said numeral keys into the path of the said stop member for arresting the sliding movement of the setting wheel, whereby the stepped roller can only actuate the setting wheel after the sliding motion of the latter is completed.
- 10 3. In a typewriter calculating machine, a device for transmitting to a counting mechanism the numerical values set up by the numeral keys, comprising the combination with a shaft capable of being operatively connected to and disconnected from a power driving mechanism, a stepped roller fixed on said shaft and capable of performing one revolution for each depression of a numeral key, and a setting wheel operatively connected to the stepped roller for transmitting the motion of said roller to the counting mechanism, said setting wheel being capable of sliding longitudinally of said stepped roller, of a slidable actuating member operatively connected to said setting wheel, a spring connected to said actuating member and adapted to displace said actuating member and setting wheel in one direction into a position for transmitting the required motion to the counting mechanism, displacing means operatively connected to said shaft and in engagement with said actuating member adapted to displace said member and setting wheel in the opposite direction against the action of said spring, said displacing means being capable of allowing said actuating member to slide under the action of said spring simultaneously with the rotary movement of the stepped roller and subsequently returning the actuating member to its initial position in opposition to the said spring, and means operatively connected to the numeral keys for arresting said actuating member and setting wheel, as and for the purposes set forth.
- 15 4. In a typewriter calculating machine, a device for transmitting to a counting mechanism the numerical values set up by the numeral keys, comprising the combination with a shaft capable of being operatively connected to and disconnected from a power driving mechanism, a stepped roller fixed on said shaft and capable of forming one revolution for each depression of a numeral key, and a setting wheel operatively connected to the stepped roller for transmitting the motion of said roller to the counting mechanism, said setting wheel being capable of sliding longitudinally of said stepped roller, of a slidable bar 70 operatively connected to said setting wheel so as to be capable of sliding the latter, a toothed wheel having a hub, and operatively connected to the shaft of the stepped roller so as to be capable of rotation by said shaft with a transmission ratio of 1:1, a rotary disc on said hub, a spiral spring connected to said hub and to said rotary disc, a pin on said rotary disc, a spring connected to said bar and adapted to displace said bar and setting wheel in one direction into position for transmitting the required motion to the counting mechanism, a stop member on said bar capable of engaging said pin on the rotary disc under the action of the spring connected to the bar, a boss on said rotary disc, a stop member 75 22 operatively connected to said shaft of the stepped roller so as to be capable of being moved into the path of the boss on said rotary disc after said disc has turned through half a revolution after the depression of a numeral key, so as to stop the movement of the rotary disc and stress the spiral spring during the second half of the revolution, said stop member being movable out of the path of said boss towards the end of the revolution of the said toothed wheel so as to release the boss and allow the rotary disc to complete the second half of its revolution under the action of the spiral spring and return the slidable bar to its initial position, and means operatively connected to the numeral keys for arresting said actuating member and setting wheel, as and for the purposes set forth.
